ALEXANDER BERNHARD DRÄGER, OF LUBECK, GERMANY.

BREATHING BAG FOR SELF-CONTAINED BREATHING APPARATUS.

Application filed April 13, 1922. Serial No. 552,070.

To all whom it may concern:

Be it known that I, ALEXANDER BERNHARD DRÄGER, a German citizen, residing at Lubeck, Germany, have invented certain new and useful Improvements in Breathing Bags for Self-Contained Breathing Apparatus, of which the following is a specification.

This invention relates to a self-contained breathing apparatus for use in noxious gases and the like, and more particularly refers to improvements in and relating to the breathing bag of such apparatus which as is well known is principally composed of a cartridge having an air purifying charge adapted for the absorption of carbonic acid from the exhaled air, breathing pipes controlled by breathing valves, an oxygen container and a breathing bag, which parts are so put together in the well known way that the exhaled air passes through or contacts the purifying charge and is breathed in again as purified air with or without revivifying oxygen, while any excess of the purified or revivified air passes into the breathing bag.

Before such an apparatus is put into use, the breathing bag, and the lungs also as much as possible must be emptied of ordinary respirable air, up to four-fifths of which, as is well known, consists of nitrogen. The reason for this is that if too much nitrogen remains in the air within the apparatus, the person wearing the same is constantly subjected to a lack of oxygen, because as soon as the oxygen in the breathing bag is used up, he will then receive only nitrogen into his lungs. This deficient supply of oxygen to the blood might be manifested by the wearer of the apparatus soon becoming insensible.

Contamination of the air in the apparatus can also be caused by traces of poisonous gases getting into the apparatus from outside, when during inhalation a certain decrease or reduction of pressure is produced and the apparatus is not perfectly air tight all over in all its several parts. Traces of such inhaled poisonous gases may accumulate during the course of the action of breathing to a dangerous extent, especially since the poisonous gases entering the apparatus invariably remain therein. It must be remembered that it is possible for such a danger to occur in every self-contained

breathing apparatus because a certain increase of pressure is produced on exhalation and a certain reduction of pressure on inhalation, as otherwise no movement of the air takes place.

These disadvantages can be obviated or at any rate reduced to a minimum, if the breathing bag be so constructed that it has a tendency and the power to set itself in a flat extended or deflated position and thereby automatically empty itself. In the breathing bags hitherto usually employed and not provided with any appropriate means of deflation, such automatic setting of the bag into the flat position is not possible. According to this invention the object aimed at is attained by providing the breathing bag with suitably formed and arranged extending or pressing springs, which tend to spread or set the breathing bag in its flat position or hold it flat. Such a breathing bag will be entirely emptied of air by its own action at the beginning of the action of inhaling. On the other hand such a breathing bag provided with means for holding it emptied, will, owing to its being still more or less inflated during the operation of breathing, immediately force air into the apparatus to support respiration when due to a deep inhalation any reduction of pressure occurs in the air-circulating system of the apparatus thereby preventing or obviating any injurious suetional action of the reduced pressure on any leaking places in the apparatus.

The use of an extending or self-emptying breathing bag may in some circumstances render exhalation somewhat difficult. This disadvantage is however so small in comparison with the advantages secured that it can well afford to be ignored.

In the accompanying sheets of drawing is shown more diagrammatically in Figure 1 a constructional example of a breathing bag constructed according to this invention. Figure 2 shows another modification in which the means tending to empty the bag are constructed in the form of clamping springs adapted to embrace and press together the side walls of the bag. Figure 3 is a cross-sectional view on the line A—B of the Figure 2, and Fig. 4 is a view illustrating the bag of Fig. 1 in operative combination with an apparatus with which it may be used.

As a self-contained breathing apparatus of the kind in question is well known, no detailed description of the same is needed.

The breathing bag *s* (Fig. 1) of any suitable configuration and size is provided at one side in well known manner with an opening *o* into which there is inserted a coupling ring *i* known per se, by means of which the breathing bag is connected to the air duct of the apparatus. The breathing bag *s* is externally provided, approximately in the middle of its four edges, with pockets *q*. Into these pockets there are inserted, with their turned down or rounded off ends, the four resilient wire yokes *n* in the manner shown in Figure 1. The free ends of these externally applied wire yokes, tending to spring apart, have co-operatively the tendency to force outwards the middle or centre parts of the four edges of the breathing bag, in order in this way to keep the bag stretched flat and to cause its two walls to bear tightly against each other.

In the example shown such stretching yokes *n* are only applied to one flat side of the breathing bag, but they may also be provided on both flat sides of the bag or alternately upon the one end and the other flat side.

The arrangement selected for the stretching yokes permits adjustment from the exterior of the bag and gives the bag a very great capacity of movability in all directions, so that the person carrying the apparatus is not hampered in his movements in any way.

According to the constructional form shown in Figures 2 and 3 the keeping flat, or the return of the inflated bag *s* to the flat position, is not effected by means of stretching springs but by means of pressure or clamping springs which are pushed like clips upon the edges of the breathing bag and act with their shoulders or legs from both sides against the lateral walls of the breathing bag and thus tend to press the respirable air out of the breathing bag and flatten the breathing bag.

For connecting the bag *s* to the air duct of the breathing apparatus the said bag has an aperture *o* with a coupling ring *i* of known type inserted therein. A number of suitably distributed clamping springs are pushed upon the edges of the bag in a clip-like manner. Each clamping spring consists of a spiral portion *t*, wound from a piece of wire, with spring-action legs *u* and *u*¹ which, in order to secure a greater surface of pressure, are provided with annular discs *x* and *x*¹ or the like of rigid material. The legs of the clamping springs springing together press, by moving the side walls towards each other, upon a decrease in the inflation or tension of the breathing bag, a corresponding quantity of air out of the

breathing bag and into the air duct of the breathing apparatus, whereby in a similar manner as through the stretching springs of Figure 1 prejudicial suction-effects caused by any pressures being under the atmospheric pressure and occurring at leaky parts of the apparatus are prevented.

The attachment of the clamping springs to the breathing bag as a security against falling off, may be effected in any suitable manner, for instance, as shown in the figures, in that the legs of the individual clamping springs are sewn by means of a couple of stitches *y* and *y*¹ to the edge or rim of the breathing bag, or they may be buttoned on by means of small loops or any other system may be adopted.

The clamping springs give the breathing bag a good capacity for movement in all directions so that the person carrying the breathing apparatus furnished with the said bag is not hampered in his movements in any way.

For the purpose of illustrating a practical installation of the invention, the bag of Fig. 1 is shown in Fig. 4 in operative combination with an apparatus with which it may be used. This apparatus comprises a mouth piece 10 connected by means of a breathing pipe 11 to an exhalation valve 12 located in a valve chest 13 and a pipe 14 connects this valve chest with the upper end of an air purifying cartridge or absorber 15. The lower end of the latter is connected by means of a pipe 16 to an inhalation valve 17 in said valve chest 13 and an inhalation pipe 18 connects the latter with the mouth piece 10. The pipe 16 which constitutes part of the air duct of the apparatus, is connected also with the breathing bag *s* by means of the coupling ring *i* and, by means of a branch pipe 19, it communicates with an oxygen bottle 20, a reducing valve 21 being preferably located in said branch pipe 19 as shown. The bag *s* shown in Figs. 2 and 3 may be similarly connected with the same apparatus which may operate in the well known and customary manner. It will be understood that the arrangement shown in Fig. 4 is only an example of a practical utilization of the invention.

I claim:

1. The combination of a breathing bag for self-contained breathing apparatus and means located exteriorly of the bag for automatically deflating the latter to expel its contents.

2. The combination of a breathing bag for self-contained breathing apparatus and resilient devices located exteriorly of the bag for automatically flattening the same to deflate said bag and expel its contents.

3. The combination of a breathing bag for self-contained breathing apparatus including side walls and externally located clamp-

ing means acting upon said side walls to automatically flatten said bag and expel its contents.

4. The combination of a breathing bag for self-contained breathing apparatus and externally located clamping springs extending over the edges of said bag to automatically flatten the same and thereby expel its contents.

10 5. The combination of a breathing bag for self-contained breathing apparatus, externally located clamping springs extending

over the edges of said bag to automatically flatten the same and thereby expel its contents and pressure members carried by said 15 springs at their free ends.

6. The combination of a breathing bag for self-contained breathing apparatus, externally located clamping springs extending over the edges of said bag to automatically 20 flatten the same and thereby expel its contents and means whereby said springs are secured to the bag.

ALEXANDER BERNHARD DRÄGER.
